UNITED STATES PATENT OFFICE.

WALTER J. BRAY, OF ARLINGTON HEIGHTS, ILLINOIS, ASSIGNOR TO BENJAMIN ELECTRIC MANUFACTURING COMPANY, OF CHICAGO, ILLINOIS, A CORPORATION OF ILLINOIS.

POWER-PRESS.

1,121,066.

Specification of Letters Patent. Patented Dec. 15, 1914.

Application filed January 8, 1913. Serial No. 740,404.

To all whom it may concern:

Be it known that I, WALTER J. BRAY, a citizen of the United States, residing at Arlington Heights, in the county of Cook, State of Illinois, have invented certain new and useful Improvements in Power-Presses, of which the following is a specification, reference being had to the accompanying drawing.

10 In the operation of power presses that are used for stamping, punching and shaping operations accidents frequently occur to the operator of the machine resulting in maiming one or both of his hands by reason of his failure to withdraw his hand or hands from beneath the descending head that carries the punch or die.

The object of my invention is to provide a simple construction of mechanism applicable to such presses that will necessitate the withdrawal of both of the attendant's hands from the path of the said head before the head can be started on its downward or operating movement. Broadly speaking I accomplish this by providing the machine with two locking devices, one adapted to be operated by the attendant's right hand and the other by his left hand, one of such devices engaging some portion of the mechanism that controls the effective movement of the head and the other one of the devices engaging and holding in locking position said first device, whereby said first device before it can be released from engagement with the controlling mechanism must itself be disengaged from the other device.

The specific construction and arrangement of the devices in which my invention is embodied are shown in the drawings and will be hereinafter described. It is to be understood, however, that I do not confine myself to the specific form and arrangement of parts shown as changes therefrom to adapt the invention to different styles and kinds 45 of machines can be readily made without departing from the spirit of the invention.

In the drawing: Figure 1 is a front elevation of a press of ordinary construction with my improvements applied thereto; Fig. 2 is an enlarged horizontal section at line 2-2 of Fig. 1 through the frame of the press, and showing in plan view my improvements; and Fig. 3 is a side elevation, partly in section, of the upper portion of the

press of Fig. 1 with my improvements attached thereto.

Referring to the several figures of the drawing in which corresponding parts are indicated by like reference characters: A indicates the frame of an ordinary press, 60 and B the supporting legs or standards therefor.

C is the driving-shaft provided with the usual fly-wheel D.

E indicates the usual sliding head that is 65 operated through the shaft C whenever the attendant releases a clutch by pressure on the foot-treadle F that pulls down a connection, such as G.

H indicates the bed of the press. 70

Inasmuch as the parts so far mentioned are common in machines of this character it is not believed further description of their construction or operation is necessary.

Referring now to my improvements by 75 the use of which immunity against crushing or maiming of the attendant's hands is furnished: 5 indicates a bent lever pivoted at 6 (see Fig. 3) to the frame of the machine and at one side of the bed thereof. Its inner upturned end extends beneath a button 7, or an equivalent piece, on the connection G that is adapted to be pulled down by pressure of the attendant's foot on the treadle F. With the upturned inner end of 80 the lever thus engaging the part 7 it is evident that the connection cannot be pulled down to release the clutch that holds the head E in raised position. The forward end of the lever 5 is best made to extend a short 85 distance in front of the bed of the machine and may be provided with a suitable head 8 for the attendant to press upon when moving the lever down. 9 indicates another 90 lever at the opposite side of the machine, its forward end being preferably provided with a head 10 similar to the head 8 on the lever 5. The inner end of this lever 9 is secured to one end of a rock-shaft 11 extending across the machine in the back part of the 95 throat thereof so as to be out of the way of the work inserted into the machine and out of the path of the punch or die carried by the head E. At the other end of the rock-shaft 11 is secured a short arm 12. The 100 parts 9, 11 and 12 might of course be formed of a single piece and hence may be considered, taken together, as a single bent lever.

The part 11 is journaled in ears 13. The short arm member 12, when the parts are in locking position, has its outer end engaged in a notch 14 formed in the inner upturned end portion of the lever 5, as shown in Fig. 3. The engagement of this member 12 with the lever 5 is normally maintained by a suitable spring 15 coiled around the shaft member 11, one end of the spring being secured to the member 11 and its other end being connected to one of the ears 13. Still another spring, 16, is shown connected at one end to the frame of the machine and at the other end to the inner upturned end 15 of the lever 5, for insuring the normal retention of that lever in engagement with the trip connection. The form, location and arrangement of the springs can of course be varied to suit different conditions and different machines.

In operation, after the attendant has placed the work to be operated upon in proper position in the machine, before he can cause a movement of the head that carries the punch or die by pressing down as usual with his foot upon the treadle F, he must first press down upon the lever 9 which will cause the short arm member 12 to be withdrawn from engagement with the lever 5, and then while still holding down such lever 9 must press down on the lever 5, which latter action on his part will turn such lever on its pivot 6 and away from the button 7, or equivalent piece that may be used in place thereof. From this it will be seen that both hands of the attendant must be withdrawn from the machine after placing material therein and before he can operate the machine through the releasing mechanism that is set in operation through the movement of the treadle. By the use of my improvements, therefore, not only is the danger of injury to the hands of the operator entirely removed but an effective safety guard is provided against accidental operation of the machine by unintentional move-

ment of the treadle. When the pressure of the attendant's hands on the levers is released in order that he may remove the material from the press the springs connected with the levers will instantly return the levers to their locking positions.

What I claim as my invention and desire to secure by Letters Patent is,—

1. In a press, the combination of a movable head, and means for reciprocating said head, comprising a clutch, a foot-lever for throwing said clutch into operation, a hand-lever adapted normally to prevent the actuation of said foot-lever, and a second hand-lever adapted normally to prevent the actuation of said first-named hand-lever.

2. In a press, the combination of a movable head, and means for reciprocating said head, comprising a clutch, a foot-lever for throwing said clutch into operation, a hand-lever, yielding means tending to hold said hand-lever in position to prevent the actuation of said foot-lever, a second hand-lever, and yielding means tending to hold said second hand-lever in position to prevent the actuation of said first-named hand-lever.

3. In a press, the combination of a movable head, and means for reciprocating said head, comprising a clutch, a foot-lever, operative connections between said clutch and said foot-lever, a stop-device mounted on said connections, a hand-lever adapted normally to engage said stop-device to prevent an operative stroke of said foot-lever but adapted to be turned out of engagement with said stop-device, and a second hand-lever adapted normally to engage said first-named hand-lever to prevent its movement out of contact with said stop-device but adapted to be turned out of engagement with said first-named hand-lever.
